CLAIM

The ornamental design for a web adjuster, as shown and described.

DESCRIPTION

FIG. 1 is a rear isometric view of a web adjuster showing an embodiment of our new design;

FIG. 2 is a front isometric view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a right elevation view thereof;

FIG. 8 is a left elevation view thereof;

FIG. 9 is a rear isometric view of a web adjuster showing a second embodiment of our new design;

FIG. 10 is a front isometric view of FIG. 9;

FIG. 11 is a top plan view of FIG. 9;

FIG. 12 is a bottom plan view of FIG. 9;

FIG. 13 is a rear elevation view of FIG. 9;

FIG. 14 is a front elevation view of FIG. 9;

FIG. 15 is a right elevation view of FIG. 9; and,

FIG. 16 is a left elevation view of FIG. 9.

The broken lines in the Figures show portions of the web adjuster which form no part of the claimed design.
